UNITED STATES PATENT OFFICE.

SUMNER A. ELY, OF YONKERS, NEW YORK, ASSIGNOR TO ELY-NORRIS SAFE COMPANY, OF PERTH AMBOY, NEW JERSEY, A CORPORATION OF NEW JERSEY.

SAFE.

No. 909,568.

Specification of Letters Patent. Patented Jan. 12, 1909.

Application filed March 28, 1908. Serial No. 423,803.

To all whom it may concern:

Be it known that I, SUMNER A. ELY, a citizen of the United States, residing at Yonkers, in the county of Westchester and State 5 of New York, have invented a certain new and useful Improvement in Safes, of which the following is a specification.

This invention concerns safes, vaults and the like, and has reference particularly to 10 the construction of the doors therefor.

The object of the invention is to provide a door for a safe of an improved construction, the improvements being directed to making the locking mechanism for the door 15 more reliable and effective and guarding against unwarranted entrance to the safe by the employment of an explosive.

The invention involves the provision of a door for a safe constructed to provide one or 20 more chambers within the door and preferably nearer the outer face than the inner face, in which gases present in an explosion may expand, these chambers being closed at the edge of the door by thin metal which 25 may be readily ruptured, and this metallic closure for the chambers being set in a slight distance from the edge of the door so as to form a trap in which an explosive in liquid form will be caught.

30 The preferred embodiment of my invention is illustrated in the accompanying drawings, in which—

Figure 1 is a central section through the door and a portion of the safe; Fig. 2 is a 35 rear face view of the door and a portion of the safe, the latter being broken away and sectioned in part; and Fig. 3 is a detail view illustrating a slight modification.

Referring to these drawings, 1 indicates 40 the wall of the safe or vault, in which is a circular opening to receive the door 2. This circular door may be supported in the usual manner, permitting it to be swung around on pivots into its opening in the wall of the 45 safe and then turned on its axis to lock it in position. For the purpose of thus locking the door, the latter is provided with radial lugs or projections 3, which coact with radial lugs or projections 4 on the wall of the opening 50 for the door in the safe 1, the projections 3 passing through the spaces between adjacent projections 4 when the door is moved to the closed position. The door 2 is

formed to provide one or more chambers 5, therein, between the front and rear faces of 55 the door and preferably nearer the front face. The sections of the door on either side of the chambers 5 are joined by one or more integral webs 6, and the several chambers 5 preferably communicate so as to form 60 in effect a single large chamber. Chambers 5 are closed at the edge of the door by a wall of thin metal which may be readily ruptured. In the manufacture of the door 2, the chambers 5 are so formed as to be open 65 at the edge of the door and afterwards a strip of sheet-metal 7 is secured in position, as shown in Fig. 1, so as to close the chambers 5, this strip extending entirely around the door. In securing strip 7 in position, 70 the strip is set back from the edge of the door a slight distance, as shown in Fig. 1, so as to provide a narrow space 8, in which a liquid explosive inserted between the door 2 and wall 1 would be trapped, and the 75 strip 7 is so thin that on the explosion of this liquid the strip would be instantly ruptured, so as to allow the gases to expand within the chambers 5.

In Fig. 3, I have shown a slight modification of the construction illustrated in Fig. 1, this consisting in the provision of a strip 9 which corresponds to the strip 7, and which is considerably thinner at one edge than at the other. This strip is mounted in 80 position within the chambers 5 with the outer face of the thicker portion flush with the edge of the door. A small chamber 10 is thus provided extending around the edge of the door adjacent to the thinner portion 85 of strip 9, which will serve to trap a liquid explosive.

When the door is inserted in its opening in the wall 1 and turned so as to bring the projections 3 and 4 into coaction, it is locked 95 in this position by either or both of two independent locks, a combination-lock and an automatic time-lock, each of these locks having its individual bolt-work. One of these locks, preferably the combination-lock, 100 is located within the chamber 5, between the outer and inner sections of the door. This lock is shown in Fig. 1 and consists of one or more bolts 11 operated by a lever 12, this lever being operated in turn by a plurality of notched disks 13. These disks are

rotated in the usual manner by a gear 14 meshing with a gear 15 on a spindle 16 which extends through the outer section of the door 2 and is provided with an operating handle 17 on its outer end. The base of the operating handle 17 is provided with scale markings in the usual manner, coöperating with similar markings on an annulus adjacent to which the base of the handle turns 10 to indicate the required extent of turning movement of the handle 17 in order to operate the combination-lock. As shown in Fig. 1, the strip 7 is provided with openings through which the ends of bolts 11 may pass, 15 the ends of these bolts being adapted to enter openings 18 provided in the wall of the opening in the safe for door 2.

The automatic time-lock 19 is secured to the inner face of the door and is arranged 20 to operate bolts 20, which pass through openings in lugs formed on the rear face of the door and the ends of which are adapted to enter openings 21 provided in the wall of the opening for door 2. The time-lock is 25 of any usual or suitable construction, it being provided preferably with a plurality of time mechanisms, three such mechanisms being shown in Fig. 2 at 22, 23 and 24. As is usual in such automatic time-locks, any 30 one of the several time mechanisms may operate the lock to release the bolts 20 at the desired time and permit them to be withdrawn from the openings 21 by a suitable spring provided for this purpose.

As will readily be seen, with a door constructed as above described, a liquid explosive inserted in the crack between the wall 1 and door 2 will become trapped in the narrow space between the door-jamb and 40 the strip 7 or the narrow portion of the strip 9, and when this explosive is detonated the strip 7 or 9 will be instantly ruptured and the gases will expand within the chambers 5. If the explosion is sufficiently severe, the front section of the door, that is, 45 the portion lying in front of the chambers 5, will be blown out, but the section of the door lying in rear of the chambers 5 will remain in place and prevent access to the 50 interior of the safe. Also, by providing two locks which are entirely independent, each having its individual bolt-work, a much more secure and reliable locking of the door is effected.

With the arrangement of these locks here shown, that is, one mounted within the chamber 5 and the other secured to the rear 55 face of the door, the parts of the two locks are not so cramped as to render their operation any the less reliable, and yet space

within the safe available for the storage of valuables is not taken up by these locks.

Having now described my invention, what I claim as new therein and desire to secure by Letters Patent is as follows:—

65

1. In a safe, a door formed of rigidly connected front and rear sections and having a chamber between said sections, said chamber extending outwardly toward the edge of the door and being closed at said edge by a readily destructible wall, substantially as set forth.

2. In a safe, a door formed of rigidly connected front and rear sections and having a chamber between said sections, said chamber extending outwardly toward the edge of the door and being closed at said edge by a readily destructible wall and said wall being positioned to provide a narrow chamber between it and the door-jamb when the door is closed, substantially as set forth.

75

3. In a safe, a door having a chamber formed therein between its front and rear faces, and a thin metallic strip secured to the door in position to close said chamber at the edge of the door, substantially as set forth.

80

4. In a safe, a door having a chamber formed therein between its front and rear faces, and a thin metallic strip secured to the door in position to close said chamber at the edge of the door, said strip being set back from the edge of the door to provide a narrow chamber between it and the door-jamb when the door is closed, substantially as set forth.

95

5. In a safe, a circular door formed of rigidly connected front and rear sections and having a chamber between said sections extending outwardly to the edge of the door, and a strip of sheet-metal extending around the door and closing said chamber at the edge of the door, substantially as set forth.

100

6. In a safe, a circular door formed of rigidly connected front and rear sections and having a chamber between said sections extending outwardly to the edge of the door, a strip of sheet-metal extending around the door and closing said chamber at the edge of the door and a lock mounted on the door within said chamber, the bolts of said lock passing through openings in said strip, substantially as set forth.

105

This specification signed and witnessed this 13th day of March, 1908.
